SPONGE UNDERLAY FOR CARPETS

Warner L. Newton, Los Angeles, Calif., assignor to The
Rubber Corporation of California, Garden Grove,
Calif., a corporation of California

Filed Oct. 19, 1959, Ser. No. 57,965

Term of patent 14 years

(Cl. D92—4)

FIG. 1.

FIG. 2.

FIG. 3.

Figs. 2, 3 and 4 are sectional views, taken along planes corresponding, respectively, to lines 2—2, 3—3 and 4—4 of Fig. 1.

I claim:

The ornamental design for a sponge underlay for carpets, substantially as shown.
